UNITED STATES PATENT OFFICE.

CLINTON JUSTICE WAGNER, OF MEMPHIS, TENNESSEE.

WOOD CONCRETE-FORM.

1,101,592.

Specification of Letters Patent. Patented June 30, 1914.

Application filed April 16, 1913. Serial No. 761,626.

To all whom it may concern:

Be it known that I, CLINTON J. WAGNER, a citizen of the United States, residing at Memphis, in the county of Shelby and State of Tennessee, have invented certain new and useful Improvements in Wood Concrete-Forms, of which the following is a specification, reference being had to the accompanying drawings.

10 This invention relates to new and useful improvements in molds and more particularly to concrete structure molds, the main object of the invention being to provide suitable bracing means whereby the side 15 walls of the mold structure are securely held in an upright position during the forming of the walls.

Another object of the present invention is to provide a bracing device for the mold 20 structures, which is pivotally connected to the walls thereof and is adjustably mounted so that the same may be readily secured to the wall at any desired height, the device being also removable so that it may be 25 readily transported from place to place.

A further object of the invention is the provision of a device of the above character which will possess advantages in points of efficiency and durability, is inexpensive to 30 manufacture and at the same time is simple in construction and operation.

With the above and other objects in view, the invention consists in the novel features of construction, and the combination and arrangement of parts, hereinafter more fully described, pointed out in the claims and shown in the accompanying drawings, in which,

Figure 1 is a side elevation of the bracing 40 device illustrating the wall structure in transverse section; Fig. 2 is a longitudinal sectional view of the lower end of the bracing member; Fig. 3 is a top plan view, the adjusting means being removed; Fig. 4 is a 45 transverse sectional view taken on the line 4-4 of Fig. 2; Fig. 5 is a detailed top plan view; and Fig. 6 is a longitudinal detailed sectional view.

In carrying out my invention, I first provide the side walls 1 of the mold which may be formed in any desirable manner and are supported by the side posts 2, which are preferably disposed in a substantially vertical position and are secured to the side 55 walls 1 by means of the transverse bolts 3. The side walls 1 are suitably supported by

means of the brace members 4, each brace member comprising two spaced parallel bars or beams, the outer ends of which are hingedly secured to the posts 2 by means of the spacing block 5, the lower end of which is rigidly secured between the members of the bracing posts by means of the bolts 6.

Hingedly secured to the lower ends of the posts 2 and arranged upon the outer side 65 of the structure are the supporting beams 7, said beams being arranged in spaced parallel relation and each of the same being hingedly secured to the lower ends of each section of the posts 2 by means of the plates 8, the other ends of said plates being secured to the beams 7 by means of the bolts 9. The outer ends of the beams 7 are securely held against movement by means of a U-shaped stirrup 10, the ends of which are securely bolted, by means of the bolts 11 to the ends of the beams 7. The intermediate portion of the stirrup 10 is engaged over a rigid stake 12, which is preferably driven into the ground, but may be secured in any other 80 suitable manner.

Secured to the upper faces of the beams 7 are the guiding bars 13 which are secured to the beams 7 by means of the lag screws 14. The guiding bars 13 are arranged in spaced 85 relation and the ends thereof securely retained in spaced relation by means of the blocks 15. The guiding bars are also secured together by means of the bolts 16, which pass through the ends of the guide 90 bars and through the block 15. The lower ends of the brace members 4 are arranged between the guiding bars 13 and are securely held in position by means of the bolts 17.

Mounted upon the lower ends of the brace members 4 is an angular plate 18 having integral side walls formed thereon, one end of said plate resting upon the guide bars and the other end engaging the brace members 100 4. The plate 18 is held securely in position by having the bolt 17 passing therethrough and through the block 19, said block retaining the bracing members 4 in spaced relations and is secured in position by said 105 brace members, by means of the transverse bolts 20.

Mounted upon the lower end of the bolt 17 and arranged within the recesses 21 formed in the upper faces of the beams 7 110 is an elongated washer 22, the ends of which are arranged beneath the guiding bars 13

to securely hold the lower ends of the bracing members 4 in position. Securely bolted to the beams 7 and arranged in spaced relation with the angular plate 18 is a guiding member 23 provided with a threaded opening in which is mounted a screw 24, one end of which is provided with a head 25, forming a reduced neck portion 26 which is adapted to be arranged within an opening 10 in the plate 27, the head of the bolt being disposed within an opening formed in the vertical portion of the plate 18. Secured to the outer end of the screw 24 is a removable head 28 which may be either rectangular in form, or of any other suitable form desired, so that a wrench or other tool may be quickly applied thereto and rotate the screw, and brace the lower end of the bracing members 4.

20 It will be readily apparent that when it is desired to move the form, the beams 7 are released from the stake 12 by withdrawing the tapering keys 29 which are inserted between the ends of the beams and the stake 25 12. A cross pin 30 is arranged in the upper end of the stake 12 to prevent any upward movement of the outer ends of the beams 7.

In forming the inside pilasters, which carry the beams, girders and the concrete floor slabs or hollow tile, I provide a horizontal member 31, the inner edge of which is supported by the walls 1, while the body portion thereof may be supported in any suitable manner. Thus, as the walls of the 30 building are formed, the inside pilasters may be also formed at the same time. After the walls of the building have been formed up to the first floor, the forms are then put in place upon the second floor and 35 arranged in alignment and lined with the walls of the lower floor. When this is done the stake 12 is eliminated as the fastening means for holding the beams 7 in place and in place of the stake 12, the beams are 40 securely held by means of a bolt 32 which is adapted to pass down through a block 33 arranged between the beams 16 and which is provided with tapering side walls. The bolt 32 passes through the beams 7 and 45 through the member 31 and in passing through the concrete flooring of the first story, a pipe 34 is mounted upon the bolt so that the same may be readily withdrawn. The bolt also extends through the member 50 31 so as to rigidly hold the beams 7 in position. Driven in between the spacing blocks 35 and the block 33 are the tapering keys 36 which are adapted to securely hold the bolt 32 against movement and at the same 55 time rigidly secure the beams 7 to the member 31 and the floor slab 37.

In Fig. 6 I have illustrated a slightly modified form of means for adjustably securing the lower ends of the brace members 4.

60 In this form I substitute a wooden block 38

for the angular plate 18. This block 38 is mounted upon the lower ends of the brace members 4 and securely held in position by means of the bolt 17. The lower end of the brace member is adjusted to various positions by means of the tapering keys 39 which are arranged within the groove 21 and disposed upon opposite sides of the elongated washer 22. Thus by the insertion and withdrawal of the keys 39, the lower end of 70 the brace member 4 may be adjusted to various positions. The mounting of the guiding bars 13 and the elongated washer 22 will be the same as shown and described in the preferred form of the invention. 75

In using my improved concrete form the same is placed in position ready for use as clearly illustrated in Fig. 1. The concrete mixture is poured into the walls 1 until the wall up to the first floor has been formed. 80 The side walls of the form are then removed and placed upon the floor slab 37, the beams 7 being first released by removing the tapering keys 29 and disengaging the stirrup 20 from the upper end of the stake 90 12. After the forms have been raised to the second floor the beams 7 are secured in place by inserting the bolts 32 through the beams and through the floor slab 37 and the member 31. The keys 36 are then arranged in 95 position to securely hold the beams 7 in place.

It will be readily apparent from the foregoing description, taken in connection with the accompanying drawings, that I have 100 provided a simple and durable adjustable supporting device for concrete molds whereby the side walls of the molds will be securely retained in an upright position during the pouring and hardening of the concrete. It will also be apparent that the device can be quickly and readily set up ready for use or easily taken down when it is desired to transport the device from place to place. 105

110 It is obvious from the above that my device is extremely simple in construction and can be manufactured at a comparatively low cost.

While I have shown and described the 115 preferred form of my invention, it will be obvious that various changes in the details of construction and in the proportions may be resorted to for successfully carrying my invention into practice without sacrificing any of the novel features or departing from the scope of the appended claims. 120

Having thus fully described my invention what I claim and desire to secure by Letters Patent is:

125 1. A device of the class described including a mold wall, an upright post arranged upon the outer side of said wall, supporting beams hingedly secured to the lower end of said post, means for rigidly securing the 130

outer end of said supporting beams, brace members having their upper ends pivotally secured to said post, an angular plate secured to the lower ends of said brace members, a bolt removably connecting the plate and the lower ends of the brace members to the supporting beams, and an adjusting screw carried by the supporting beams and engaging the plate to adjust the lower ends 10 of the brace members with respect to the beams.

2. A device of the class described including a mold wall, a post arranged upon the side of said wall, supporting beams having 15 the inner ends hingedly secured to said post, means for securing the outer ends of said beams, brace members having their upper

ends secured to said post, spaced guides secured to the outer ends of said beams, an angular plate secured to the lower end of 20 said brace members, a bolt extending through the plate and the lower end of the brace members and below the guides, an elongated washer disposed between the head of the bolt and the guides, and an adjusting screw movably mounted upon the outer ends 25 of the supporting beams and having its inner end engaging the angular plate whereby the adjustment of said screw will rigidly adjust the lower ends of the bracing members. 30

CLINTON JUSTICE WAGNER.
